DESIGN FOR A SIGN

Hy Hammer, Chicago, Ill., assignor to Price Bros.,
Inc., Chicago, Ill., a corporation of Illinois

Application July 14, 1934, Serial No. 52,591

Term of patent 3½ years

To all whom it may concern:

Be it known that I, Hy HAMMER, a citizen of the United States, residing at Chicago, in the county of Cook and State of Illinois, have invented a new, original, and ornamental Design for Sign, of which the following is a specification, reference being had to the accompanying drawing, forming a part thereof.

In the drawing:

The single figure is a perspective view of my sign.

I claim:

The ornamental design for a sign, as shown.

In witness whereof, I hereunto subscribe my name, this 5th day of July, 1934.

HY HAMMER.
